(57) **CLAIM**

The ornamental design for a wireless repeater housing, as shown and described.

DESCRIPTION

FIG. 1 is a top plan view of a wireless repeater housing showing our new design;

FIG. 2 is a front elevation view thereof.

FIG. 3 is a right side elevation view thereof, with the left side being a mirror image thereof.

FIG. 4 is a top plan view thereof; and,

FIG. 5 is a bottom plan view thereof.

The structure shown in broken lines in FIGS. 1 through 5 is for illustrative purposes only and forms no part of the claimed design.
